United States Patent Office.

ISRAEL KEPLER, OF CORRY, PENNSYLVANIA.

Letters Patent No. 70,858, dated November 12, 1867.

IMPROVEMENT IN FIREPLACES.

The Schedule referred to in these Letters Patent and making part of the same.

TO ALL WHOM IT MAY CONCERN:

Be it known that I, ISRAEL KEPLER, of Corry, in the county of Erie, and State of Pennsylvania, have invented certain new and useful Improvements in Air-Heating Fireplaces; and I do hereby declare the following to be a full, clear, and exact description of the same, reference being had to the accompanying drawings, making a part of this specification, in which—

Figure 1 represents a front view of the fireplace, with a portion of the breast and jamb broken away to show the fire and flue-back.

Figure 2 represents a transverse vertical section through the fireplace and air-heating chamber.

Figure 3 represents a top plan of the gas-flue and air-heating chamber, and hot-air passage or pipe.

Figure 4 represents a horizontal section of the fireplace, taken through the red line $x x$ of fig. 1.

Similar letters of reference, where they occur in the separate figures, denote like parts in all of them.

I am aware that an air-heating chamber has been used in connection with a fireplace. I am also aware that a corrugated grate-back has long been known and used. These things I do not lay any claim to.

My invention consists in the use of a corrugated flue and breast-plate above the fire-box or grate, in connection with the air-heating chamber behind it, so as to increase the heating surface, as also to prevent said flue-plate or back from cracking.

To enable others skilled in the art to make and use my invention, I will proceed to describe the same with reference to the drawings.

A represents the breast of the fireplace; B, the jambs; C, the grate-bars; D, the fire-box; E, the ash-pit, and F the air-heating chamber behind the grate. The grate-back G is corrugated, as is common; and the corrugations have been so made as to match the spaces between the grate-bars, to allow the ashes to run down. This involves the necessity of always procuring grate-backs and grates from the same pattern, which is often impossible, and always inconvenient. I make the ridges of the corrugations, as seen at a , fig. 4, so that they may just touch or set upon the back bar of the grate, and thus leave ash-flues, without requiring the grooves of the corrugations and spaces between the grate-bars to match. From the top of the corrugated grate-back G I extend a corrugated flue-back, H, upwards and forward over the fire-box, so as to take the more intense heat of the fire and burning gases, and thus not only very much increase the radiating surface, but prevent that flue-back or plate from cracking by its great expansion and contraction, the corrugations admitting of expansion and contraction in a very great degree without cracking. The throat of the flue, by the use of the corrugated plate H, will be of the form and shape shown at $b b b$, fig. 3. The plates G and H may be cast in one piece; but I prefer to cast them in two parts, c being the joint between them, so that, if one should burn out or crack before the other, both would not have to be renewed.

The air to be heated in the chamber F may enter at the opening d , and, when heated, pass through the hot-air pipe I, and out at e , into the room in which the fireplace is used, or in the room above or alongside of it, as is commonly done. J is the top plate of the hot-air chamber F. The pipe I passes through this plate, as also through the smoke-flue, as seen in fig. 2.

Having thus fully described my invention, what I claim, is—

In connection with the common corrugated grate-back, the corrugated extension-plate or back H, projecting over the fire, and continuing up to the throat of the flue, as and for the purpose herein described and represented.

ISRAEL KEPLER.
